Primary Examiner — Anhdao Doan(74) *Attorney, Agent, or Firm* — Banner & Witcoff, Ltd.(57) **CLAIM**

The ornamental design for a X-ray tube for medical device, as shown and described.

DESCRIPTION

FIG. 1 is a perspective view of a X-ray tube for medical device showing our new design,

FIG. 2 is a front elevational view thereof,

FIG. 3 is a rear elevational view thereof,

FIG. 4 is a right side elevational view, a left, side elevational view being a mirror image thereof,

FIG. 5 is a top plan view thereof; and,

FIG. 6 is a bottom plan view thereof.

The long-short broken lines represent the bounds of the claim, and all other broken lines are directed to environment and are for illustrative purposes only. None of the broken lines form a part of the claimed design.
